(57) **CLAIM**

The ornamental design for an egg mold pan, as shown and described.

DESCRIPTION

FIG. 1: is a top perspective view of the egg mold pan showing my new design;

FIG. 2: is a bottom perspective view thereof;

FIG. 3: is a top view thereof; and,

FIG. 4: is a section view taken along 4-4 in FIG. 1 view thereof.

The broken lines shown in the drawings are for illustrative purposes only and form no part of the claimed design.
